PULLEY OR SIMILAR ARTICLE

Howard F. Gerland, Bridgeport, Conn., assignor to Garden Specialties, Incorporated, Bridgeport, Conn., a corporation of Connecticut

Application December 7, 1955, Serial No. 39,193

Term of patent 14 years

(Cl. D41—1)

Fig. 1 is a perspective view of a pulley or similar article, showing my new design;

Fig. 2 is a side elevation thereof; and

Fig. 3 is an edge view thereof.

The characteristic feature of my design for the pulley disclosed resides in the yoke member having the configuration shown.

I claim:

The ornamental design for a pulley or similar article, substantially as shown and described.
